MATCH PACK

David H. Warner, Akron, Ohio

Application September 26, 1939, Serial No. 296,577

2 Claims. (Cl. 206—29)

My invention relates to match packs and has for its object to provide a match pack wherein the igniting ends are permanently retained within the enclosing pack strip, and means are provided for readily removing the matches from said enclosing pack strip.

It is common practice for matches to be vended and used in what is known as a pack, wherein the match shanks are formed of some sustaining and slowly inflammable material such as strips of cardboard impregnated with inflammable material and the match heads are formed of a chemical adapted to ignite when frictionally rubbed on a chemically impregnated strip, which when so rubbed sets up the conditions to effect ignition. As ordinarily prepared these match packs are adapted to have the enclosing strip pulled out to open up the entire group of matches, and when the match is struck and ignited sparks may and do fly to the other matches, igniting the entire pack and causing serious burns.

It is the particular object of my invention to provide a simple and efficient match pack wherein the heads are at all times protected so that no matter how the ignition sparks may fly they cannot reach the unignited heads of the match pack and this frequently very serious accident cannot take place.

It is a further object of my invention to provide a match pack wherein the heads of the matches in single or multiple rows are entirely enclosed within the pack strip, which has its ends secured at the bases of the matches and a loop of the strip permanently formed about and over the igniting heads of the matches, together with means to permit reaching the base of the match shanks, so that the same may be separated from the pack and the matches withdrawn laterally from the pack.

It is a further object of my invention in carrying out the above-named purposes to provide a match pack of the type wherein the ends of the pack strip are permanently secured and the ignition heads of the matches are held closed within the loop of the match strip, and to provide at the base of the match strip means for opening up said base whereby the matches may be successively removed through the open sides of the match pack without exposing the heads of the matches still held in the pack.

The full objects and advantages of my invention will appear in connection with the detailed description thereof and the novel features of my invention whereby the important advantageous

results above defined are obtained are particularly pointed out in the claims.

In the drawing, illustrating an application of my invention in one form—

Fig. 1 is a view of a match pack with the matches enclosed therein showing the manner in which the heads are enclosed and protected and how successive strips of the casing are provided adapted to be removed successively to permit the matches to be withdrawn laterally, these strips extending half-way across the package.

Fig. 2 is a view similar to Fig. 1, showing the reverse side with slits and strips similarly arranged.

Fig. 3 is a sectional view taken on line 3—3 of Fig. 1.

Fig. 4 is a view of a modified form showing slits and removable strips all the way across one side of the match pack with some strips and matches removed.

Fig. 5 is a view similar to Fig. 4, showing the manner of removal of a match.

Fig. 6 is a sectional view on line 6—6 of Fig. 4.

In the form of the invention shown in Figs. 1 to 6, the pack comprises the customary group of strip match shanks 10 with match heads 11 of a chemical substance adapted to ignite when frictionally engaged with a friction surface of another suitable chemical substance. The package 30 of matches 10, as is customary, are shown in double rows, about which is bent a pack strip 12 forming a loop 13 surrounding the heads, as clearly shown. The strip 12 is formed with a multiplicity of slits 14 extending half-way across the strip on opposite sides, as clearly shown in Figs. 1 and 2, and extending all the way across on one side, as shown in Figs. 4 and 5. Or the slits may extend all the way across on both sides if desired. These slits are toward the ends of 35 the strips which are bound together by staples 15. The customary layer of friction paste 16 is laid on one surface where the ends of the pack strips are bound together, and a similar layer of friction paste 17, may if desired, be placed on the opposite side, as indicated in Figs. 1 to 3. The slits 14 provide a multiplicity of intervening strips 18 which are shown in Figs. 1 and 2 as being formed from the center outwardly on opposite sides of the pack strip. It will be apparent that by inserting the thumb nail in a slit 14 the corresponding strip 18 may be removed, as indicated at 19 of Fig. 4. When a strip has been removed shanks 10 of matches under that strip will be exposed and the match can be pulled out 40 edgewise from the adjacent open sides of the

match pack as indicated at 20 of Fig. 1, and 21 of Fig. 5. It will be obvious that all matches under the opening through the pack casing 12 formed by the removal of strip 18, will be removed before a succeeding strip 18 is taken out, and this is true whether the half-way sets of strips of Figs. 1 and 2, or the full length set of strips of Fig. 5, are employed.

Ignition layers 16 and 17 of friction paste may, if desired, be placed on both sides of the pack. In this form of my invention, the heads of unused matches are thus protected from possibility of being ignited by sparks or by being ignited at any time excepting when withdrawn.

The advantages of my invention will be apparent from the foregoing specification. The manufacture of match packs embodying my invention will be no more expensive than the manufacture of match packs as at present on the market. Yet there is produced a match pack in which the igniting heads of the matches are always surrounded by the pack strip, protected from contact with outside objects, and screened from flying sparks when a match is scratched upon the igniting strip and is thereby ignited. At the same time therefore, there is protection of the heads and other objects outside of the match pack from contact and prevention of the serious accidents which might otherwise happen, and frequently do happen, with the form of match packs generally in use, of igniting the mass of match heads and causing serious burns to the one who holds the pack.

I claim:

1. A match pack comprising a body of matches held with the ends of the shanks secured and the heads free, a pack strip secured permanently at

both ends upon said shanks so as to permanently enclose the heads of the matches while the match pack is open at both sides of said matches, a series of slits in a wall of said pack strip close to the point of securing said walls together spaced apart the thickness of the matches underneath and severally overlying the match shanks beneath, said slits forming short strips which may be removed by insertion of a thumb-nail in the

10 slit to expose the shank of a match so as to enable the thumb-nail to be applied thereto, whereby the match shank may be broken sidewise at the point where held and removed laterally from one of said open sides.

15 2. A match pack comprising a body of matches held with the ends of the shanks secured and the heads free, a pack strip secured permanently at both ends upon said shanks so as to permanently enclose the heads of the matches while

20 the match pack is open at both sides of said matches, a series of slits in the opposite walls of the said pack strip close to the point of securing said matches together, spaced apart the thickness of the matches underneath and severally

25 overlying the match shanks beneath, said slits being formed to the center of the match pack from opposite edges thereof and forming short strips which may be removed by a thumb nail in the slit to expose the shank of the match so as to enable the thumb nail to be applied thereto, whereby, by successive removal of said short strips, all the match shanks in the pack may successively be broken sidewise at the points where held and removed laterally from one of said open sides.

DAVID H. WARNER.
